UNITED STATES PATENT OFFICE.

FREDERICK R. PARKER, OF BUFFALO, NEW YORK.

TELEPHONE SYSTEM.

1,115,969.

Specification of Letters Patent.

Patented Nov. 3, 1914.

Original application filed November 24, 1906, Serial No. 344,894. Divided and this application filed July 13, 1911. Serial No. 638,339.

To all whom it may concern:

Be it known that I, FREDERICK R. PARKER, a citizen of the United States of America, residing at Buffalo, in the county of Erie 5 and State of New York, have invented a new and useful Telephone System, of which the following is a specification, reference being had to the accompanying drawings, illustrating same.

10 My invention relates in general to electrical systems for transmitting intelligence, and will be hereinafter particularly described as applied to a telephone system. The principal objects of my invention are, 15 to provide improved line and supervisory signaling devices for electrical systems; to provide improved arrangements of the line and supervisory signaling devices in such systems, and improved means for operating 20 same; to provide an improved signaling device adapted for use as both a line signal and a supervisory signal, and improved means for utilizing such a signaling device; to provide an improved transfer circuit for 25 extending or transferring the connections from one switchboard to another or from one position to another, and improved means for supervising such connections; and to provide other improvements here- 30 inafter set forth.

Other objects will be apparent from the following specification.

In this present invention I employ a signal-initiating device in connection with each 35 of the lines of the electrical system, such as a telephone system, and operate such devices in series with their lines to give predetermined signals, preferably line signals, and in bridging circuits of their lines to 40 give other predetermined signals, preferably supervisory signals, in the latter case the said devices being shunted out or rendered inoperative by their lines when the circuits of the latter are closed, and allowed to 45 operate to give signals when the said line shunts are removed. Thus it will be seen that the circuits of the signal-initiating devices are changed from series circuits of the lines to bridging circuits of the lines, or 50 vice versa, for giving the different signals.

In the accompanying drawings illustrating one form of my invention, Figure 1 is a diagram showing two subscribers' telephone lines extending from respective substations to a central station, and the central station apparatus therefor; and Fig. 2 is

a diagram showing a transfer circuit to be used in connection with the system of Fig. 1, for extending or transferring the connections from one switchboard to another or 60 from one position to another.

Like characters refer to like parts in the several figures.

In the drawings, substation A is connected with the central station by a suitable 65 line circuit comprising limbs 1 and 2 which preferably terminate in contact springs 3 and 4, respectively, of a spring jack C. A signaling device D is normally connected from limb 1 of the line through contacts 70 6 and 5 of jack C, to one pole 7 of the source of electricity E, the connection to limb 1 being preferably permanently made. The other pole 8 of battery E is preferably connected through contact 9 and jack spring 75 4 to limb 2 of the line. These connections normally place the signaling device D and source of electricity E in a series circuit with the line.

At the substation A various forms of apparatus may be employed, as well understood, the apparatus illustrated being adapted to close the circuit of the line when the receiver is removed from the switch-hook, and to open the circuit of the line when the 85 receiver is hung upon the switch-hook. The apparatus of line B is the same as that of line A, and like characters have been employed to represent like parts.

In the plug-cord connecting circuit of 90 Fig. 1 the connecting plugs H and I are normally connected together through repeating coil K as shown. The central source of electricity E is bridged across the main strands of the plug-cord circuit between windings 32 and 33 and windings 34 and 35 of the repeating coil K. The operator's transmitter 36 and receiver 37 may be bridged across the plug-cord circuit by springs 40 and 41 of the listening key 100 engaging contacts 38 and 39, respectively, when depressed. The ringing key G is constructed and connected to disconnect the main strands 29 and 31 of connecting plug I from the repeating coil K, and to reverse 105 the poles of battery E on the strands 29 and 31 when depressed, springs 21 and 22 disengaging contacts 23 and 24, respectively, which are connected to poles 7 and 8, respectively, of battery E, and engaging contacts 25 and 26, respectively, which are connected to poles 8 and 7, respectively, of bat-

battery E. The purpose of reversing the battery E on the strands 29 and 31 of plug I as just described, is for operating the substation ringing apparatus F as described and claimed in my United States Patent No. 1,000,340, of which this present application is a division.

In Fig. 2 I have shown a transfer circuit adapted to be used with the system of Fig. 1, for transferring the calls or connections from one switchboard to another, or between different sections or positions of the same switchboard. The jack C₂ is provided with tip and sleeve contact springs 48 and 49, respectively, which are connected to limbs 50 and 51, respectively, of the transfer circuit, which limbs terminate in tip and sleeve strands 52 and 53, respectively, of transfer plug J. A transfer signaling device M is connected from tip spring 48 of jack C₂, through a plug-seat switch 55, 54 at plug J, to limb 51 of the transfer circuit. Jack C₂ and plug I are at one operator's position, and plug J and ringing key N are at another operator's position, or at another switchboard. Ringing key N is adapted to reverse the poles of battery E on the main strands 52 and 53 of transfer plug J when depressed, the same as key G reverses the poles of battery E on strands 29 and 31 of plug I, springs 56 and 57 disengaging contacts 58 and 59, respectively, and engaging contacts 60 and 61, respectively.

The operation of the system is as follows: If subscriber A desires to talk with subscriber B, he lifts his telephone receiver from the switch hook, in the usual manner, and thereby closes a circuit of battery E from pole 7 through contacts 5 and 6, signaling device D of line A, limb 1 of the line, substation A, limb 2 of the line, jack spring 4, and contact 9 to pole 8 of battery E, which causes current to flow over this circuit sufficiently to actuate the signaling device D and cause same to give a signal for connection. In answer to the line signal of signaling devices D, the operator inserts answering plug H into jack C of line A, thereby disengaging jack spring 4 from contact 9, and engaging the spring 4 with contact 6 which is thereby disengaged from contact 5. Now the circuit of battery E is closed through winding 32 of repeating coil K, tip strand 28, jack spring 3, limb 1 of the line, substation A, limb 2 of the line, jack spring 4, sleeve strand 30, and winding 34 of repeating coil K, the signaling device D being now bridged across this circuit from jack spring 3 through the device D and contact 6 to jack spring 4, and shunted by the relatively low resistance of the line so as to render it incapable of displaying a signal. The operator now depresses her listening key which connects her telephone set across the

main strands of answering plug H in the usual manner, for conversation with subscriber A. When the operator learns from subscriber A that he wishes connection with subscriber B, she inserts the calling plug I into jack C of line B and thereby closes a circuit of battery E from pole 7, through winding 33 of repeating coil K, tip strand 29, jack spring 3 of line B, signaling device D of line B, contact 6, jack spring 4, sleeve strand 31, and winding 35 of repeating coil K, to pole 8 of battery E. The current now flowing through this circuit energizes the signaling device D and causes same to display a signal, the line circuit being now open at substation B and therefore not shunting the device D to render it inoperative. When plug I is inserted into jack C of line B, it switches the circuits the same as described above in connection with plug H and jack C of line A, thus changing the circuit of signaling device D from a series circuit of the line to a bridging circuit of the line. The operator now depresses her ringing key G, and thereby reverses the poles of battery E on the line of subscriber B, as above stated, to ring the ringer F at substation B as a calling signal for the subscriber at substation B, as described in detail in my above mentioned United States Patent No. 1,000,340. As the operator depresses ringing key G she preferably restores her listening key to normal position, in the usual manner. When the subscriber at substation B is rung sufficiently, the operator restores her ringing key G to normal position. When the subscriber at substation B responds to his call and takes his receiver from the switch-hook, he closes the circuit of battery E over his line and thereby connects the line as a shunt around the signaling device D which is now bridged across the line as above described, to shunt the device D and thereby extinguish its signal. Now the subscribers A and B are connected for conversation with each other, both of the signals D D for the respective lines being inactive. When the conversation is completed and subscriber A hangs his receiver upon its switch-hook, he breaks the circuit of his line at his substation and thereby takes the line shunt away from his signaling device D and thus allows the latter to operate, by means of current from battery E over the circuit 32, 28, 3, D, 6, 4, 30 and 34, and display a signal for disconnection. When subscriber B hangs his receiver upon its switch-hook he causes his signaling device D to display a signal for disconnection, in a manner similar to that just described for subscriber A. If either subscriber A or B now desires to signal the operator for any purpose, he may operate his signal D intermittently by raising and lowering his switch-hook, in a manner now 130

well understood. When the operator receives both disconnect signals, from subscribers A and B respectively, she withdraws the plugs H and I from their respective spring jacks and thereby extinguishes the supervisory or disconnect signals D and D and restores all circuits and apparatus to their normal condition. If subscriber A has called for subscriber B and the latter is on another switchboard, or his jack is out of reach of the A-line operator, then it is necessary to use the transfer circuit of Fig. 2 for making the connection. In this case the A-line operator inserts the calling plug I into the transfer jack C₂ which extends the cord circuit to transfer plug J at the B-line position. Then the A-line operator instructs the B-line operator, in any suitable manner, to insert the transfer plug J into jack C of line B. When plug I is inserted into jack C₂, a circuit is closed from pole 7 of battery E through winding 33, tip strand 29, jack spring 48, signaling device M at the A-line position, plug-seat switch contacts 55 54 at the B-line position, conductor 51, jack spring 49, sleeve strand 31, and winding 35 to pole 8 of battery E, which causes signaling device M to operate, by means of current from battery E, and thereby display a signal. When the B-line operator inserts plug J into jack C of line B, she opens switch contacts 54 55, thereby opening the circuit through signaling device M and extinguishing its signal to indicate to the A-line operator that the plug J has been removed from its seat for connection with line B, and also switches the circuits of line B as described in connection with line A when plug H is inserted into jack C thereof. The signaling device D of line B now operates and displays a signal, the circuit of line B being open at the substation. The B-line operator now depresses her ringing key N and thereby rings the ringer F at substation B as hereinbefore mentioned. When subscriber B is rung sufficiently, the ringing key N is restored to its normal position. When subscriber B responds to his call and lifts his receiver from the switch-hook, he closes the circuit of his line as a relatively low-resistance shunt around his signaling device D and thereby deenergizes D and extinguishes its signal which indicates to the B-line operator that subscriber B has answered his call. The talking circuit between subscribers A and B now includes line A, the cord circuit of Fig. 1, the main strands 50 and 51 of the transfer circuit of Fig. 2, and line B. When the conversation is completed and subscriber B hangs his receiver upon its switch-hook, he breaks the circuit of his line at his substation and thereby takes the line shunt away from his signaling device D which now operates, due to the removal of the line shunt, by means of current from battery E over the circuit from pole 7, through winding 33, tip strand 29, jack spring 48, conductor 50, tip strand 52, jack spring 3 of line B, signaling device D, contact 6, jack spring 4, 70 sleeve strand 53, conductor 51, jack spring 49, sleeve strand 31, and winding 35 to pole 8 of battery E, and thereby conveys to the B-line operator the signal for disconnection. The B-line operator now withdraws plug J from jack C of line B and thereby opens the circuit of battery E through signaling device D and extinguishes its signal, at the same time restoring the circuits of line B to their normal condition. When the 75 plug J is returned to its plug seat, it closes the contacts 54 55 and thereby closes the circuit of battery E through signaling device M, over the path hereinbefore described, which device M thereupon displays a signal 80 to indicate to the A-line operator that the plug J has been removed from its jack. When the A-line operator receives this signal she withdraws the plug I from the jack C₂ and thereby disconnects battery E from 85 signaling device M and extinguishes its signal. The subscriber A gives his disconnect signal as hereinbefore set forth, whereupon the A-line operator withdraws the plug H from his jack C and thereby restores 90 all A-line circuits and apparatus to their normal condition.

If desired, the transfer circuit may be provided with a listening key similar to that of Fig. 1, to enable the B-line operator 100 to cut in on the line and talk to the subscribers.

For the signaling devices D, D and M, I may use an electric signal lamp in series with an impedance, a relay controlling a 105 signal, or other suitable electrically-operable devices. For the battery E, I may use a suitable direct-current generator if desired.

In this invention I do not wish to be 110 limited to the exact details nor to the particular apparatus or arrangements herein shown, as many modifications thereof may be made or utilized without departing from the scope of the appended claims.

What I claim as my invention is:

1. A telephone line extending from a source of electricity to a station and having a signaling device in series therewith, means for connecting the signaling device in a bridge of the line between the said source and station, and means for causing the signaling device to display a signal in each said connection.
2. A telephone line extending from a 125 source of electricity to a station and having a signaling device in series therewith, means whereby connection with the line connects the signaling device in a bridge of the line between the said source and station, and

- means for causing the signaling device to display a signal in each said connection.
3. A telephone line extending from a substation to a central station, a signaling device and source of electricity at the central station in a series circuit with the line, means at the substation for closing the said circuit to cause the signaling device to display a signal, and means at the central station whereby connection with the line changes the circuit of the signaling device from a series circuit of the line to a bridging circuit of the line between the said source and the substation, the said means at the substation now controlling the circuit of the line as a shunt to the signaling device to control the operation of same.
4. A telephone line extending from a substation to a central station, a signaling device and source of electricity at the central station, means at the central station for connecting the signaling device in series with the line and in a bridge across the line between the said source and the substation, and means at the substation for controlling the said series circuit and for controlling the circuit of the line as a shunt to the said bridge, for operating the signaling device in each said connection.
5. A telephone line extending to a central station, a signaling device and source of electricity at the central station, means for connecting the signaling device in a series circuit with the line and in multiple with the line and the said source, and means for operating the signaling device in each said connection.
6. A telephone line extending from a substation to a central station, a signaling device and source of electricity at the central station, means at the central station for connecting the signaling device in series with the line and in multiple with the line and the said source as desired, and means at the substation for opening and closing the circuit of the line as the said series circuit or as a portion of the said multiple circuit, to operate the signaling device as desired.
7. A telephone line extending to a central station, a signaling device and source of electricity at the central station, means for connecting the signaling device and source in series with the line and the signaling device in multiple with the line and the said source as desired, and means for operating the signaling device in each said connection.
8. A telephone line, a signaling device and source of electricity in series therewith, connecting means for the line, means whereby connection with the line connects the signaling device in a bridge across the line extending to the said source, and means for causing the signaling device to display a signal in each said connection.

9. An electrical transmitting line, an electrically-operable device and electrical supply associated therewith, means for connecting the said device in series with the line and in multiple with the line and electrical supply as desired, and means for operating the said device in each said connection.
10. An electrical transmitting line, an electrically-operable signaling device connected in series therewith, electrical supply, means for connecting the said device in a bridge across the line extending to the electrical supply, and means for operating the said device in each arrangement.
11. An electrical transmitting line, an electrically-operable signaling device and source of electricity normally connected in series with the line, means for connecting the said device in a bridge across the line extending to the said source, and means for operating the said device in each connection.
12. An electrical transmitting line extending from a substation to a central station, an electrically-operable device and source of electricity at the central station in series with the line, connecting means for the line, means whereby connection with the line connects the said device in multiple with the line and the said source, and means at the substation for controlling the circuit of the line to operate the said device or render same inoperative, in each connection.
13. An electrical transmitting line extending to a central station, connecting means for the line, an electrically-operable device connected to be operated by current in the line, electrical supply, and means whereby connection with the line at the central station connects the said device in a shunt circuit with the line extending to the electrical supply.
14. An electrical transmitting line, connecting means for the line, an electrically-operable device connected to be operated by current in the line, electrical supply, and means whereby connection with the line connects the said line as a shunt around the said device relatively to the electrical supply.
15. A telephone talking circuit extending from a central station to a substation, a signaling device at the central station, and a jack adapted for connecting the signaling device in series with a portion of both limbs of the talking circuit extending to the substation, and in series with a portion of both limbs of the talking circuit at the central station only, for signaling purposes.
16. A telephone talking circuit extending from a central station to a substation, a signaling device at the central station, and means for operating the signaling device in series with a portion of both limbs of the talking circuit extending to the substation to give a line signal, and for operating the signaling device in series with another por-

tion of both limbs of the talking circuit at the central station only to give a supervisory signal.

17. An electrical circuit comprising a main conductor extending from a substation to a central station and having a suitable return, signaling means normally connected with the said circuit, means for operating the signaling means in series with a portion of the said main conductor extending to the substation and the return, to give a signal, a jack adapted for connecting the signaling means in series with another portion of the said main conductor and return at the central station only, and means for operating the signaling means in the latter connection to give another signal.

18. An electrical transmitting circuit having suitable electrical supply, signal-initiating means therefor, and means for connecting the signal-initiating means in series with the said circuit to provide a signal, and for connecting the signal-initiating means across the said circuit extending to the electrical supply to provide another signal.

19. A metallic telephone line extending from a substation to a central station, a signaling device and source of electricity at the central station normally in series with the line, connecting means for the line, means whereby connection with the line changes the connection of the said source with the line and connects the signaling device across the metallic line, and means at the substation for controlling the said series circuit to operate the signaling device as a line signal and for controlling the circuit of the line as a shunt to the signaling device to operate the latter as a supervisory signal.

20. A telephone line extending from a substation to a central station, a signal-initiating device and source of electricity in series with the line at the central station when no connection is made with the line, a connecting circuit for the line, and suitable connections whereby the signal-initiating device is operated over a circuit at the central station only, including a talking strand of the connecting circuit, when connection is made with the line while the apparatus at the substation is not in use.

21. The combination with a telephone talking circuit, of a signaling device in series therewith, electrical supply, and means whereby the signaling device may be connected across the said circuit extending to the electrical supply for signaling purposes.

22. A series circuit comprising an electrical transmitting line, a signal-initiating device, and a source of electricity, and means whereby the said source may be cut out of the said series circuit and the latter closed through only the said device and line.

23. A series circuit comprising a telephone line, a signaling device, and a source of elec-

tricity, and means whereby the said source may be cut out of the said series circuit and connected in multiple with the signaling device on the line.

24. A metallic electrical transmitting line extending from a substation to a central station, an electrically-operable device associated with the line, suitable electrical supply, and manually-operable means at both the substation and the central station co-operating to operate the said device in series with the metallic line and in a bridge across the line extending to the electrical supply.

25. An electrical transmitting line extending from a substation to a central station, an electrically-operable device associated with the line, suitable electrical supply for the said device, and a switch at both the substation and the central station co-operating to operate the said device in a series circuit with the line and in a bridging circuit of the line, the circuit arrangement being such that each switch may operate the said device and render same inoperative independently of the position of the other switch.

26. In an electrical transmitting system, lines extending to a central station, an electrically-operable device for each line at the central station, electrical supply at the central station, and means at the central station whereby each said device may be connected in a series circuit with its line and in a bridge across the line extending to the electrical supply, for signaling purposes.

27. In an electrical transmitting system, lines extending to a central station, an electrically-operable device for each line at the central station, a common source of electricity for operating the said devices, and means at the central station whereby each said device may be connected in a series circuit with its line and the said source, and in a bridge across the line extending to the said source, for purposes substantially as set forth.

28. An electrical transmitting line extending to a central station, an electrically-operable device associated therewith, electrical supply, and means at the central station adapted to connect the said device in series with the line and in multiple with the line and the electrical supply, as desired.

29. In combination, a metallic telephone line extending to a central station, a signaling device, a source of electricity, a metallic connecting circuit for the line, means for establishing a circuit through the said source, the metallic line, and the said device, to operate the latter when no connection is made with the line, and means for establishing a circuit through the said source, the metallic connecting circuit, and the said device, exclusive of the exterior line, to operate the said device when connection is made with the line.

30. A telephone line extending from a substation to a central station where it terminates in suitable connection terminals, a plug-cord circuit adapted to be connected with the line, a signaling device and source of electricity in series with the line, means at the substation for closing the said series circuit to cause the signaling device to give a line signal, and means whereby connection with the line bridges the signaling device across the line to be shunted by same and thereby rendered inoperative. 65
31. A telephone line extending from a substation to a central station where it terminates in suitable connection terminals, a plug-cord connecting circuit for the line, a signaling device and source of electricity normally in series with the line, means whereby connection with the line bridges the signaling device across the line to cause it to display a signal when the apparatus at the substation is not in use, and means at the substation for closing the circuit of the line as a shunt around the signaling device to render same inoperative. 70
32. A telephone line extending from a substation to a central station, a connecting circuit for the line at the central station, a signaling device and source of electricity at the central station normally in series with the line, a switch at the substation for closing the said series circuit to operate the signaling device as a line signal, means whereby connection with the line places the latter in multiple with the signaling device to shunt same and render it inoperative, opening the line circuit at the substation now taking the shunt away from the signaling device and causing same to operate as a supervisory signal. 75
33. A telephone line extending from a substation to a central station, a connecting circuit for the line, a signaling device associated with the line, a source of electricity at the central station associated with the line and connecting circuit, means at the substation for closing the circuit of the said source through the signaling device and line when no connection is made with the line, to produce a line signal, and means whereby connection with the line places the signaling device in multiple with the line and closes the circuit of the said source through the connecting circuit and the signaling device to produce a supervisory signal while the apparatus at the substation is not in use. 80
34. The combination of two telephone lines extending to a central station, a connecting circuit for the lines, terminating in two connecting plugs, a signaling device for each line, and means for operating each signaling device in series with its line and in series with the main strands of a connecting plug to be shunted by the line and rendered inoperative. 85
35. A plurality of telephone lines, a signaling device for each line normally in series therewith, means for bridging each signaling device across its line when connection is made with the respective lines, whereby the latter may shunt the signaling devices, and means whereby each subscriber takes his line shunt away from the signaling device of his line when he is through with the line and thereby causes the signaling device to give a disconnect signal. 90
36. The combination with a telephone line extending to a central station, of a signal-initiating device at the central station, a connecting circuit at the central station, and a jack for connecting the signal-initiating device in a loop with the line, and in a loop with the connecting circuit exclusive of the exterior line, for signaling purposes. 95
37. The combination with a telephone line extending to a central station, of a signal-initiating device and electrical supply therefor at the central station, a connecting circuit at the central station, and a jack for connecting the signal-initiating device in a loop with the line and the electrical supply, and in a loop with the connecting circuit and the electrical supply exclusive of the exterior line, for signaling purposes. 100
38. An electrical transmitting line, an electrically-operable device, suitable electrical supply, means for connecting the said device in series with the line and electrical supply, means for connecting the said device in multiple with the line and electrical supply, and means for operating the said device in each of the said connections. 105
39. A telephone talking circuit, a signaling device, a jack and plug connection adapted for connecting the signaling device in series with entirely different portions of both limbs of the talking circuit at different times, and means for operating the said device in each of the said connections. 110
40. An electrical transmitting line, an electrically-operable device, suitable electrical supply, means for connecting the said device in series with the line, means for connecting the said device in multiple with the line, means for operating the said device in each of the said connections. 115
- As inventor of the foregoing I hereunto subscribe my name this 11th day of July, 1911.
